UNITED STATES PATENT OFFICE.

DAVID J. BULLINGER, OF NEW HAVEN, MISSOURI.

INTERNAL-COMBUSTION ENGINE.

1,222,600.

Specification of Letters Patent. Patented Apr. 17, 1917.

Application filed May 21, 1915. Serial No. 29,522.

To all whom it may concern:

Be it known that I, DAVID J. BULLINGER, a citizen of the United States, residing at New Haven, in the county of Franklin and

5 State of Missouri, have invented a new and useful Internal-Combustion Engine; and I do hereby declare the following to be a full, clear, and exact description of the invention, such as will enable others skilled 10 in the art to which it appertains to make and use the same.

This invention relates to the art of engines, and more especially to an improved internal combustion engine, of the multiple 15 cylinder type, in which an impulse is imparted to the piston upon every stroke thereof, and an object of the invention is to provide a simple and efficient and practical engine of this type for generating a 20 steady or uniform power.

Another object of the invention is to provide a multiple cylinder axially aligned and having an equal multiple of pistons arranged axially on a single piston rod, and which 25 piston upon every stroke receives an impulse, owing to the ignition of a charge at each end of each cylinder. Immediately before each charge is ignited, the same is compressed.

30 Another object of the invention is to provide simple and efficient means to prevent the gases from leaking past the piston rod.

A further object of the invention is to provide two combustion chambers in each 35 cylinder, one upon either side of each piston.

Another object of the invention is to provide efficient means for cooling the piston rod and the chambers.

Another object of the invention is the 40 provision of an automatic device whereby the waste lubricant may be expelled from the cylinders at regular intervals.

In practical fields the details of construction may necessitate alterations, falling 45 within the scope of what is claimed.

The invention comprises further features and combination of parts, as hereinafter set forth, shown in the drawings and claimed.

In the drawings:

50 Figure 1 is a vertical sectional view.
Fig. 2 is a rear elevation of the engine.
Fig. 3 is a longitudinal sectional view at

right angles to that shown in Fig. 1.

Fig. 4 is a combination sectional frag-
55 mentary perspective view, in other words, a dia-grammatic view, showing the multiplicity

ity of inlet and exhaust valves, and the means for controlling the same, in order to disclose the intakes of charges, and the exhausting of the utilized gases.

Fig. 5 is a cross sectional view on line 60 5-5 of Fig. 1.

Fig. 6 is a cross sectional view on line 6-6 of Fig. 1.

Fig. 7 is a cross sectional view on line 7-7 65 of Fig. 2.

Fig. 8 is a cross sectional view on line 8-8 of Fig. 2.

Referring more especially to the drawings, 1 designates the crank casing of the 70 engine, in bearings 2 of which a suitable crank shaft 3 is journaled, which shaft is provided with the usual fly wheel 4 at one end, and a gear 5 at the other end. The gear 5 meshes with the gear 6 of the stub shaft 7, 75 which is mounted in a suitable bearing 8 of the crank casing. Also carried by and rotatable with the stub shaft 7 is a beveled gear 9, which meshes with a beveled gear 10, on one end of the shaft 11, which is mounted in a suitable bearing 12, and the purpose 80 of which shaft 11 will appear later. The crank casing has a supplemental casing 13 bolted to it as shown at 14, to cover the gears 5 and 6. The crank casing 1 is also 85 constructed with an extension casing 15 having guides 16, in which the cross heads 17 are guided. Connecting the cross heads is a pin 18, on which the sleeves 19 of the forks 20 of the pitman 21 are journaled. The pitman 21 has a sleeve 22, which is journaled upon the crank 23, so that when the piston 24 is reciprocated, which piston is connected at 25 to the pin 18, revoluble movement is 90 imparted to the crank shaft 3, and from 95 which power may be transmitted in any suitable manner.

Bolted together at 26 are the multiple cylinders 27 arranged axially. One of the cylinders 27 is partially contracted as shown 100 at 28 and has a flange 29 bolted at 30 to the extension casing 15, and the piston rod 24 (which is provided with suitable packing 31) reciprocates through the bearings or sleeves 32 of said cylinders. It is to be observed that the one or more packings upon the piston rod move with the piston rod within said bearings or sleeves 32, for the purpose of preventing the gases leaking past the piston rod. This feature serves the 105 same purpose as the ordinary piston rod stuffing box of the well known double act-

ing steam engine or air compressor, and is a practical and efficient improvement over the same, for it requires no re-packing. One of the cylinders has a head 33 bolted to it as at 34. The multiple cylinders are provided with a water space or jacket 35, for not only maintaining the cylinders cool, and also the pistons, for portions of this space or water jacket 35 extend inwardly toward the sleeves or bearings 32, thereby cooling the piston rod therein. Fixed upon the piston rod (which passes axially through the multiple cylinders) are the usual pistons 36 and 37, which are provided with the usual packing 38. The lower cylinder 27 is provided with two inlets *a* and *b* and two exhaust ports *c* and *d*, which are controlled by the valves *a'*, *b'*, and *c'* and *d'*. The upper cylinder 27 is provided with two inlet ports *a²* and *b²*, and two exhaust ports *c²* and *d²*, which are controlled by the valves *a³* and *b³* and *c³* and *d³*. It will be observed that the valves *a'* and *c'* are adjacent each other, and the other valves are correspondingly arranged, and furthermore, each set of inlet and exhaust valves include valve rods 40 and 41, passing through bearings 42, there being springs 43 to hold the valve normally closed. Mounted in bearings 44 of one side portion or rear portion of the engine is an elongated shaft 45, and arranged on this shaft at spaced intervals are lever arms 46 and 47, 48 and 49, 50 and 51, and 52 and 53. The lever arms 46 and 47 are pivoted respectively to the valve rod 40 of the valves *a'* and *c'*, as shown at 50^a and 55, whereas the arms 48 and 49 are likewise pivoted to the valve rods of the valves *b'* and *d'*. The lever arms 50 and 51 are pivoted respectively to the rods of the valves *a³* and *c³*, whereas the lever arms 52 and 53 are pivoted to the rods of the valves *c³* and *d³*. Each of the lever arms 47, 49, 51 and 53 is provided with an extension 56, and this particular construction in connection with the valves is clearly shown in Figs. 4 and 6 of the drawings. The shaft 11 is mounted in additional bearings of the casing of the engine, and is provided with a worm 57, and a plurality of cams 59, 60, 61, and 62. Each of the lever arms 46, 48, 50 and 52 is provided with extensions 63 having curved portions 64. The cams 59 and 61 coöperate with the extensions 63 and 56 of the lever arms 48, 52, 49 and 53, in order to operate their respective inlet and exhaust valve, whereas the cams 60 and 62 coöperate with the extensions 56 and 64 of the lever arms 47, 51, 46 and 50, in order to operate their respective valves, to permit the inlet and the exhaust. As before stated, the shaft 11 receives its power from the crank shaft 3, therefore the various inlet and exhaust valves will be opened and closed at regular intervals, to permit charges to enter, and

allow the utilized gases to exhaust. Mounted upon a stub pin 66 of one side of the casing of the engine is a worm wheel 67, which coöperates with the worm 57. The combustion chambers 69 and 70 of the multiple cylinders are provided with lubricant from any suitable source (not shown), and to permit the outlet of the waste or excess lubricant passages 71 and 72 are provided, which passages communicate with the interiors 73 and 74 of the enlargements 75 and 76 of the pipe or conduit 77, an extension 78 of which extends to and communicates with the interior of the extension casing 15 of the crank casing. Mounted in the interiors of the enlargements 75 and 76 to coöperate with their respective seats, to control the flow of the waste or excess lubricant through the passages 71 and 72 and through said pipe 77 are valves 80 and 81, which are mounted upon the ends of a spring tensioned valve rod 82, guided through suitable bearings of the enlargements 75 and 76 of said pipe or tube or conduit 77. This valve rod 82 has a laterally extending finger 83, and projecting laterally from the pipe 77 is a lug 84. Carried by the outer face of the worm wheel and rotatable therewith is a spring arm 85, which, as the work wheel makes a complete revolution due to its meshing with the worm 57 of the shaft 11 (which receives its power from said crank shaft) comes in contact with the lug 84. As the worm wheel 67 continues its slow revoluble movement, the spring arm 85 is put under tension, and as it flies off from engagement with said lug 84 it strikes the finger 83 with sufficient force as to actuate the valve rod 82 against the tension of its spring, thereby unseating the valves 80 and 81, and the various working parts of the engine are so arranged and geared that these valves 80 and 81 are opened in this manner when the pistons 36 and 37 are moving in the direction of the arrow *g*, thereby expelling the excess or waste lubricant, which flows into the extension casing 15 and the crank casing, thereby keeping those parts well lubricated. When there is an over-efficiency of lubricant in the crank casing, it may be drained by virtue of the valve 90. As shown in Fig. 6, the multiple cylinders are provided with spark plugs 91 of the usual type, there being one of such spark plugs opposite each inlet valve.

Operation.

It is to be noted that this engine is compound or double acting in its operation, and that the piston rod and piston (which are arranged axially in cylinders, which are likewise axially arranged) receive an impulse upon every stroke, which is accomplished in the following manner: For instance, when the pistons 36 and 37 are in

their uppermost positions as shown in Fig. 1, a charge beyond the piston 36 is being compressed for immediate firing after compression, that is, at *h*, whereas the piston 37 has just finished a scavenger stroke at *k*. The movement of the piston 36 to the position shown in Fig. 1 having been the result of a charge fired at *m* below the piston 37, and when the piston 36 moves to the position shown in Fig. 1, a charge was sucked in at *n*. As soon as a charge is fired at *h*, the piston 36 and the piston 37 move in direction of the arrow *g*, in moving in this direction, the piston 36 compresses the charge which was previously sucked in at *n*, while the piston 37 scavenges its cylinder of the utilized gases of the charge which was fired at *m*. Supposing the pistons 36 and 37 are in positions opposite those shown in Fig. 1, in which case, as before stated a charge at *n* is compressed, and the piston 37 has just completed its scavenger and exhaust stroke at *m*, and immediately following the compression of the charge at *n*, said charge is fired, moving the pistons 36 and 37 upwardly again, in which case a charge is sucked in at *m*, and the utilized gases (as a result of firing at *h*) above the piston 36 are scavenged or exhausted from the exhaust valve above the piston 36. At this period when the utilized gases are exhausting above the piston at *h*, a charge is compressed, and immediately subsequently fired at *k*, as a result of which the pistons 36 and 37 are moved down again. When having been moved down again this time, the charge which was drawn in at *m* is compressed, then fired, moving the pistons 36 and 37 upwardly, in which case a charge is again compressed and fired at *h*, which is the first compression and firing as set forth in this description of the operation. In other words, compression, firing, suction and exhausting respectively occur alternately upon first one side and then the other of each of the pistons, at *h*, *k*, *m* and *n*, and in rapid succession, thereby imparting an impulse to the pistons and piston rod upon every stroke thereof, the various exhaust and inlet valves responding accordingly. The inner circumferences of the chambers 69 and 70 at their lower portions are provided with annular troughs, to guide the lubricant to the outlets 71 and 72. By this form or construction of engine it can be seen that a uniform or steady power is imparted to the crank

shaft, from which power may be transmitted in any suitable manner (not shown). In reference to the diagrammatic view shown in Fig. 4, in connection with the other illustrations of the drawings, it may be seen that the connections between the various valves and the shaft 11, are so constructed and arranged relative to one another, to carry out the various movements or working parts and the cycles of operations coördinately.

The invention having been set forth, what is claimed as new and useful is:—

In an internal multiple cylinder double acting combustion engine, the combination of an engine cylinder having a bearing sleeve at one end and intake and exhaust ports adjacent said sleeve and a second engine cylinder having a bearing sleeve at one end to be arranged axially with the first bearing sleeve when the two cylinders are joined axially together, of a piston rod reciprocating in said bearing sleeves and provided with pistons operating respectively in said cylinders, means for connecting the cylinders, the second cylinder having a cylinder head secured thereon, said cylinder head having adjacent intake and exhaust ports, the second sleeve being integral with the second cylinder, four ports, two being intake ports on one side of the second sleeve, the other two being exhaust ports on the other side of the second sleeve, the two cylinders having water jackets common to and in communication with each other, the cylinder head having a water jacket partially surrounding its intake and exhaust ports and in communication with the water jacket of the second cylinder, thereby keeping said ports cool, the water jacket of the first cylinder extending partially about its intake and exhaust ports, the water jacket of the second cylinder partially curving about each of its four ports and entirely surrounding the central portion of said sleeve, to keep the ports, the sleeve and piston rod cooled, means for operating the rod, valves for said ports, and a mechanism connected to said valves and operated by said means for operating the valves.

In testimony whereof I have signed my name to this specification in the presence of two subscribing witnesses.

DAVID J. BULLINGER.
